Des. 220,101
Patented Mar. 9, 1971

220,101

WATER FAUCET

George Z. Brown and Roger H. Ramsey, Akron, Ohio,
assignors to Standard Screw Company, Hartford, Conn.

Filed Aug. 18, 1969, Ser. No. 18,751

Term of patent 14 years

Int. Cl. D23—01

U.S. Cl. D23—23

FIG. 1 is a side elevational view of a water faucet showing my new design;

FIG. 2 is a top plan view thereof;

FIG. 3 is a front elevational view thereof;

FIG. 4 is a plan view taken from a plane parallel to the top of the faucet control handle; and

FIG. 5 is a fragmentary perspective view of the lower portion thereof.

We claim:

The ornamental design for a water faucet, as shown.
